UNITED STATES PATENT OFFICE.

JOHN O. VAN BUSKOR AND ERNEST MEIER, OF DWIGHT, ILLINOIS.

WATER-HEATER.

1,079,811.

Specification of Letters Patent. Patented Nov. 25, 1913.

Application filed July 22, 1913. Serial No. 780,602.

To all whom it may concern:

Be it known that we, JOHN O. VAN BUSKOR and ERNEST MEIER, citizens of the United States, residing at Dwight, in the 5 county of Livingston, State of Illinois, have invented a new and useful Water-Heater, of which the following is a specification.

The device forming the subject matter of this application is a water heater, adapted 10 to constitute a part of a boiler of any sort, the device being so constructed that the products of combustion passing into the smoke box, will effect a heating of the water before the same enters the boiler.

15 The invention aims to provide a structure which will not only heat the water, in the smoke box, before the water enters the boiler, but, as well, to trap and remove sediment, before the water enters the boiler.

20 It is within the scope of the invention to improve generally and to enhance the utility of, devices of that type to which the present invention appertains.

With the above and other objects in view 25 which will appear as the description proceeds, the invention resides in the combination and arrangement of parts and in the details of construction hereinafter described and claimed, it being understood that 30 changes in the precise embodiment of the invention herein disclosed can be made within the scope of what is claimed without departing from the spirit of the invention.

In the drawing:—Figure 1 shows in top 35 plan, a boiler equipped with the device constituting the subject matter of this application, parts being broken away; Fig. 2 is a side elevation of the structure shown in Fig. 1; Fig. 3 is a transverse section through the 40 smoke box; Fig. 4 is a longitudinal section through the smoke box.

In the drawings, the numeral 1 indicates the shell of a boiler, the numeral 2 denoting the boiler head and the numeral 3 indicating 45 the smoke box.

A stack is shown at 4 and a flue sheet shown at 5, the flues being indicated at 6.

The injector is shown at 7. A pipe 8 lies outside of the boiler shell 1 and communicates with the injector 7. Interposed in the 50 pipe 8 is a check valve 9 which closes toward the injector 7.

Located outside of the boiler shell 8 is a pipe 10 in which is interposed a hand valve 55 11. The rear end of the pipe 10 communicates with the water space of the boiler.

Located in the smoke box 3 and held in place by stay bolts 23 or in any other suitable manner, is a coil of pipe, indicated at 12, the same comprising any desired number 60 of convolutions. The axis of the coil 12 is coincident with the axis of the boiler shell 1. Each convolution of the coil 12 is provided in its lowermost portion with a valve controlled drain cock 14 which extends downwardly through the bottom of the boiler shell 1. The end of the rear convolution of the coil 12 is connected as indicated at 15 to the pipe 8 and the end of the forward convolution of the coil is connected as indicated 70 at 16 to the pipe 10.

The outer forward convolution of the coil 12 is denoted specifically by the numeral 17, and interposed in the convolution 17 as shown to best advantage in Fig. 3 is a mud 75 drum 18. The drum 18 comprises a reduced neck 19 having flanges 20 which are secured to the shell 1, the lower end of the mud drum 18 being tapered as indicated at 21. The tapered lower end of the mud drum 18 communicates with a pipe 22 which extends downwardly through the bottom of the boiler shell 1. In the pipe 22 and outside of the shell 1 is a valve 25. The neck 19 carries a tube 26, the inner end of which projects toward the longitudinal axis of the mud drum, the outer end of the tube 26 entering the extremity of the outer convolutions 17 of the coil. The tube 26, constitutes, to all intent and purposes, a part of the outer convolution 80 85 90 95 100 105 110 of the coil 12.

In practical operation water is delivered by the injector 7 into the pipe 8, the water passing through the check valve 9 and entering the rear convolution of the coil 12 by 95 way of the connection 15. The water is thus disposed immediately in advance of the flue sheet 5, and, as the water passes through the coil 12, the water is heated and products of combustion which pass out of the flues 6 into 100 the smoke box 3 and thence pass out of the boiler shell 1 through the stack 4. The water traverses one convolution after another of the coil and ultimately enters the pipe 10, by way of the outermost convolution 17 of 105 the coil. By means of the pipe 10, the water, in a heated condition, is discharged into the water space of the boiler. The check valve 9, opening away from the injector 9, serves to prevent the boiler pressure from 110 acting as a back pressure against the injector 7. In this connection, it is to be noted

that the coil 12 at all times stands full of water, the coil being in communication with the water space of the boiler. Therefore, the coil cannot be burnt out. However, if 5 desired, the valve 11 may be closed manually, thereby cutting off the coil 12 from communication with the water space of the boiler. As the water traverses the outermost convolution 17 of the coil 12, the water 10 passes across the mud drum 18. Any sediment in the water will be received by the mud drum and the drum may be drained off by opening the valve 25. Owing to the fact 15 that the tube 26 is provided, the mud and sediment in the drum 18 is prevented from foaming up into the convolution 17 and then passing by way of the pipe 10 into the boiler. All of the convolutions of the coil 12 may be drained by opening the cocks 14.

20 The device herein disclosed is of simple form, but, it is so constructed that a great saving of fuel will be effective, the products of combustion being rendered effective, to heat the water, before the same enters the 25 boiler. All foreign matter in the water will be removed and trapped by the mud drum 18.

Referring to Fig. 3 it will be noted that two of the connections 15 are shown. This construction permits the device to be used 30 upon engines which employ two injectors.

Having thus described the invention, what is claimed is:—

In a device of the class described, a boiler including a shell, a flue-sheet defining a 35 smoke box in the boiler, and a stack com-

municating with the smoke box; a single helical coil of pipe in the smoke box, the rear convolution of the coil being located close to the flue sheet, the end of the rear convolution of the coil being extended outside of the boiler; a source of water supply 40 communicating with said end of the rear convolution of the coil; a mud drum secured directly to the top of the shell in advance of the stack and acting as a deflector to facilitate the progress of the products of combustion through the stack; a pipe leading from the bottom of the mud drum through the shell; and a valve in said pipe; the forward convolution of a coil consisting of two 45 axially aligned portions, one of which portions at its outer end communicates with the water space of the boiler, the other end of which enters the mud drum and protrudes inwardly beyond the inner face of the mud 50 drum to form an anti-foaming nozzle, the other of said portions of the forward convolution of the coil entering the mud drum and terminating at its inner end substantially flush with the inner face of the mud 55 drum and opposite to the anti-foaming nozzle.

In testimony that we claim the foregoing as our own, we have hereto affixed our signatures in the presence of two witnesses.

JOHN O. VAN BUSKOR.
ERNEST MEIER.
